UNITED STATES PATENT OFFICE.

ERNEST A. WILLIAMSON AND IRA W. WILLIAMSON, OF GREENEVILLE, TENNESSEE.

BROOM.

1,064,271.

Specification of Letters Patent. Patented June 10, 1913.

Application filed March 3, 1913. Serial No. 751,950.

To all whom it may concern:

Be it known that we, ERNEST A. WILLIAMSON and IRA W. WILLIAMSON, citizens of the United States, residing at Greeneville, in the county of Greene and State of Tennessee, have invented certain new and useful Improvements in Brooms, of which the following is a specification, reference being had to the accompanying drawings.

10 This invention relates to new and useful improvements in brooms and more particularly to a means for securing the broom to the handle and our object is to provide an improved device of this character which 15 will secure the broom head to the handle and at the same time retain the straws in place throughout the use thereof.

A further object of the invention resides in providing a bonnet or cover for the 20 broom head and still another object resides in providing a device which is simple and durable in construction, inexpensive to manufacture and one which will be very efficient and useful in operation.

25 With these and other objects in view, the invention consists in the novel features of construction, combination and arrangement of parts as will be hereinafter referred to and more particularly pointed out in the 30 specification and claim.

In the accompanying drawing forming a part of this application, Figure 1 is a perspective view of the device partly in section. Fig. 2 is a vertical section therethrough. 35 Fig. 3 is a horizontal section through the same as seen on line 3—3, Fig. 2.

In describing our invention, we shall refer to the drawing in which similar reference characters designate corresponding parts 40 throughout the several views and in which—

1 indicates the broom proper and 2 the handle therefor, extending through the head of the same. Wrapped tightly around the broom head, adjacent its extreme upper end, 45 is a metallic band 3 which has a portion thereof disposed through the head and engaged with the lower portion of the handle 2. This band forms a substantial clamping means for retaining the broom to the handle 50 and at the same time secures the straws in

place. Also encircling the broom head at a point slightly below the band 3, is a heavy wire 4 which also extends inwardly to be rigidly engaged with the extreme lower end of said handle member 2. This wire member 4 steadies the broom on the handle and also serves a purpose to be hereinafter and more particularly described.

Extending over the head of the broom and receiving the handle 2 therethrough, is a 60 cloth bonnet or cover 5, which fits tightly about the broom head and has the lower edges thereof wrapped around the wire 4 and stitched in place. This cloth bonnet gives the broom a neat finish and at the same 65 time aids in the retention of the straws in place at their upper ends.

The metal band 3 and the wire band 4, together with the bonnet 5, are applied to the broom in the manufacture thereof, although 70 these members may be applied to any broom now in use and it will be seen that with the use of such members, the life of a broom will be considerably increased and the value of the broom itself enhanced.

75 From the formation of this broom, it will be noted that the stalks are bound together and the tops or butts thereof cut off, thus forming the shoulder at the head thereof and this shoulder and the upper portion of 80 the broom proper is then covered by the cloth bonnet above referred to. Thus the laborious and expensive bending of the fiber of the corn over and into engagement with the handle as is now the case, is 85 eliminated and a much cheaper form of device substituted therefor. In this cheap formation of the broom, a device is presented which is equally, if not more, durable and efficient than the brooms formed by 90 the more expensive means above referred to.

95 From the foregoing it will be seen that we have provided a simple, inexpensive and efficient means for carrying out the objects of the invention and while we have particularly described the elements best adapted to perform the functions set forth, it is obvious that various changes in form, proportion and in the minor details of construction may be resorted to without departing from the spirit. 100

or sacrificing any of the principles of the invention.

Having thus described this invention, what we claim is:—

- 5 A broom consisting of broom straws, a handle member disposed therethrough, a pair of clamping bands encircling said straws and having portions thereof engaged with the handle, a textile bonnet covering 10 the upper portions of said straws and having

the lower edges thereof engaged with the lower clamping band.

In testimony whereof we hereunto affix our signatures in the presence of two witnesses.

ERNEST A. WILLIAMSON.
IRA W. WILLIAMSON.
